4 Claims. (Cl. 77—64)

The invention relates to a device for automatically adjusting slides or tables or the like, more particularly co-ordinate tables, of machine tools, through the agency of cams determining the position in which the slides or the like are set up.

It is an object of the invention to enable a large number of positions associated with the lengthwise and transverse movements of an adjustable slide or the like to be stored in readily adjustable and repeatable fashion, for instance, so that drilling machines can drill workpieces having a large number of bores in series without the use of templates or jigs or the like.

Devices of this kind are known, but in most of them the control cams are disposed in a single plane in adjacent grooves, with the result that the limited space means that only a relatively small number of grooves can be provided.

According to the invention, the cams are disposed on the periphery of control drums in driving engagement with the slides or the like. Preferably, the cams are disposed on the outer periphery of clamping rings which clamp automatically on the drum.

For a better understanding of the invention and to show how the same may be carried into effect, reference may now be made to the accompanying drawings wherein:

FIGURE 1 is a diagrammatic side elevation of a co-ordinate table having two control drums;

FIGURE 2 is a plan view of the table shown in FIGURE 1;

FIGURE 3 is a cross-section through a control drum, the detector and the setting pin;

FIGURE 4 is a section taken along the line IV—IV of FIGURE 3, and

FIGURE 5 is a longitudinal section through a control drum.

A work table 3 shown in FIGURES 1 and 2 has in known manner a base 1 on which a cross-slide 2 is mounted in readily movable manner, for instance, by means of anti-friction bearings; an electric motor (not shown) can move the slide 2 in a direction y. The table 3 is so mounted on the slide 2, for instance, via anti-friction bearings, as to be movable in a direction x by means of an electric motor (not shown). The slides 2 and 3 can be operated by motor drive units controlled by control switches in a simple control circuit as shown in United States Patent 2,648,237 issued August 11, 1953. One end of each of two steel bands 4a, 4b is secured to the table 3; their other ends are rigidly secured to the cylindrical periphery of a drum 5 which is mounted on the slide 2 and which is connected via a shaft 6 to a control drum Wx. The drum Wx rotates through slightly less than 360° for a movement of the table 3 over the whole of its travel. Also mounted on the slide 2 is a drum 7 whose axis is perpendicular to the drum 5. The drum 7 has a cylindrical periphery; secured thereto are the ends of two steel bands 8a, 8b whose other ends are rigidly secured to the base 1. Consequently, when the slide 2 performs the whole of its travel in the y direction, the drum 7 rotates through less than 360°. This rotation is transmitted by two face gears 9 to a shaft 10 having a control drum Wy secured to its end. The two

drums Wx, Wy are therefore disposed one beside another and have their axes parallel with one another. Special means which do not form part of this invention and which are therefore not described ensure that the movements of the slide 2 and table 3 are transmitted without backlash to the drums Wx, Wy.

The two drums Wx, Wy are of basically similar construction, and so only the drum Wx is shown in FIGURES 3—5. As is diagrammatically shown in FIGURES 10 3 and 4, a number of clamping rings 11 are clamped fast to the drum Wx and have sufficient clamping action on their own not to be dislodge on the drum surface by forces produced by the detector elements. The clamping rings 11 each have two inclined surfaces 12 which 15 serve as cams, are disposed exactly 180° opposite one another and form transition surfaces between a raised part 11b and a recessed part 11a of the periphery of the rings 11. A detector 13 detects the periphery of each ring 11 and co-operates with electric switches 14, 15 controlling the motor operating the table 3. All that will be 20 mentioned here is that the table 3 is stopped and secured in the dead correct position whenever apex 13a of the detector 13 is in the centre of the cam 12.

Each ring 11 is formed with a through radial slot 16 25 which widens radially outwards wedge-fashion, and the slots 16 are disposed in a plane E_v which is offset by an angle $\alpha=90^\circ$ from the horizontal plane E_h passing through the centres of the cams 12. A support member 17 which is disposed above and extends along the drum 30 Wx has passages 18 all disposed in the plane E_v. The spacing between the passages corresponds to the spacing between the individual rings 11; as can be seen in FIGURE 5, in actual practice the spacing is determined by spacer rings. The passages 18 are adapted to receive pins 35 19 having a wedge-shaped end 20 whose wedge angle is the same as the wedge angle of the slot 16.

To re-set a ring 11 in order to store a new table position, the electrical detecting and drive system is first started to bring the table into the position determined by 40 the particular ring 11 concerned, such position being shown in FIGURE 3, whereafter a pin 19 is introduced into the passage 18 and pressed right home so that the ring 11 is expanded and becomes a loose fit on the drum Wx. The table 3 is then moved into the new position and carefully adjusted, whereafter the pin 19 is removed 45 so that the ring 11 clamps the drum Wx tightly again to "memorise" the new position of the table. The table can be returned to this new position whenever required by automatic detection. The slide 2 can be controlled by the drum Wy in just the same way.

A practical form of the drum Wx is shown in FIGURE 5. As will be apparent therefrom, two clamping rings 11 are disposed below each passage 18 in order that a very large number of clamping rings may be provided for a given length of the drum Wx. In this case, the pins 19 55 have a wedge-shaped portion 20 extending over only half their cross-section so that they can expand either one ring 11 or the other in two positions 180° apart from one another. The support member 17 has two bearings 21 for the drum Wx. In order that the rings 11 may be slid on, one end of the drum is conical and has a head 22 which is secured to the drum Wx by screws 23. The head 22 is formed with a groove 26 engaged by a plate 24 providing axial location of the whole drum Wx. A spring strip 24a which can be loaded by a nut 25 also 60 engages in the groove 26 to enable the drum Wx to be clamped fast with the support member 17.

The drum Wx is driven by shaft 6 via a sleeve 27 and 65 collet chuck 28. A cup spring 31 presses the jaws 30 of the chuck 28 against a cylindrical inside surface 29 of the drum Wx and is in turn loaded via a sleeve 32 by a

loading screw 33, so that its periphery is increased and it forces the jaws 30 against the surface 29.

The device hereinbefore described can provide a neutral movement. When the rings 11 have been set up to a particular programme, for instance, a drilling pattern, but the workpiece chucked on the table 3 is still in the wrong position relatively to the drum Wx, the table 3 can be accurately adjusted, either by hand or by means of an optical adjusting system, relatively to the co-ordinates of the first drilling operation once the nut 25 has been tightened and the screw 33 slackened. During this adjustment the drum Wx moves relatively to its drive shaft 6. Once the adjustment has been made, the screw 33 is re-tightened and the nut 25 slackened. The drum Wx is then correctly positioned relatively to the workpiece.

What I claim is:

1. In a device for automatically controlling the movement of motor operated cross slides having an electric control switch in a motor control circuit comprising a support, rotatable drum means mounted in said support, means drivingly connecting one cross slide to the drum for rotation in said support, a series of split rings clampingly mounted on said drum to rotate therewith, cam projections on each of said rings to actuate the electric control switch during rotation of said drum, a series of guide openings in said support arranged in radial alignment with said rings, a pin selectively mounted in at least one of said openings with its inner end presented to said rings, whereby said drum means may be moved into registry with the split portion of one of said rings and forced inwardly to expand a selected ring and release its clamping action on said drum, said pin also arresting movement of the selected ring while the drum is moved to various positions.

2. In a device as set forth in claim 1 in which the split portion of each of said rings forms a slot having outwardly and radially inclined surfaces forming a V-shaped

through notch and in which the end of the pin is correspondingly shaped to expand the ring selected and release its gripping action on the drum.

3. In a device as set forth in claim 1 in which two control drums are provided, one for each slide and in which the means for drivingly connecting the slides to the drums includes a collet chuck for connecting the drums to their respective drive means, and the chuck jaws are adapted to be expanded by a cup-shaped spring which is screw loaded and in which means are provided to clamp each control drum in a fixed position relative to said support so that the work table or slide can be adjusted relatively to either control drum for a predetermined work program set up by preselecting the positions of certain clamping rings.

4. In a device as set forth in claim 1 in which the cross slides embodies a slide and a coordinate cross work table slide, and in which the drum means comprises a pair of drums in which the means for drivingly connecting the slides to the drums includes flexible straps for converting sliding movement of the slides to rotational movement of the drums.
